US0D1048203S

(12) **United States Design Patent** (10) **Patent No.:** **US D1,048,203 S**
(45) **Date of Patent:** **** Oct. 22, 2024**

(54) **INFLATABLE DEVICE**

- (71) Applicant: **FUNBOY, LLC**, Seattle, WA (US)
(72) Inventors: **Blake Miller Barrett**, Seattle, WA (US); **Maxwell Page Barrett**, Seattle, WA (US)
(73) Assignee: **FUNBOY, LLC**, Seattle, WA (US)
(**) Term: **15 Years**
(21) Appl. No.: **29/944,439**
(22) Filed: **May 28, 2024**

Related U.S. Application Data

- (63) Continuation of application No. 29/879,083, filed on Jun. 30, 2023.

CLAIM

The ornamental design for an inflatable device, as shown and described.

DESCRIPTION

FIG. 1 is a top, front, right-side perspective view of an inflatable device, showing the new design; FIG. 2 is a bottom, back, left-side perspective view thereof; FIG. 3 is a front view thereof; FIG. 4 is a back view thereof; FIG. 5 is a right-side view thereof; FIG. 6 is a left-side view thereof; FIG. 7 is a top view thereof; FIG. 8 is a bottom view thereof; FIG. 9 is a top, front, right-side perspective view showing the inflatable device in use; FIG. 10 is a front view thereof; and, FIG. 11 is a right-side view thereof.

The dashed broken lines depict environment and portions of the inflatable device that form no part of the claimed design. The dot-dashed broken lines represent boundaries of the claimed design and form no part of the claimed design.

1 Claim, 11 Drawing Sheets
